COMBINED NURSING BOTTLE CONTAINER AND SUPPORT

Morris J. Berry, % Fashioncraft-Excella,
87 34th St., Brooklyn, N.Y.

Filed Feb. 1, 1963, Ser. No. 73,399

Term of patent 14 years

(CL. D83—8)

FIG. 1

FIG. 2

FIGURE 1 is a front elevational view of a combined nursing bottle container and support showing my new design. The slide fastener closure is understood to continue throughout the broken line area shown therein;

I claim:

The ornamental design for a combined nursing bottle container and support, substantially as shown and described.
